CHARLES A. AHLSTROM, OF JAMESTOWN, NEW YORK.

PIANO-ACTION.

SPECIFICATION forming part of Letters Patent No. 736,920, dated August 25, 1903.

Application filed November 3, 1902. Serial No. 129,824. (No model.)

To all whom it may concern:

Be it known that I, CHARLES A. AHLSTROM, a citizen of the United States, and a resident of Jamestown, in the county of Chautauqua and State of New York, have invented a new and useful Piano-Action, of which the following, taken in connection with the accompanying drawings, is a full and clear description.

My invention relates to piano-actions; and the object of my invention is to provide a positive uniform means for controlling or regulating the position of the back-check as against climatic changes and which prevents the back-checks and hammers from blocking solidly against the strings and stopping all sound and which also provides an effective check for the hammers when brought into close proximity to the strings in producing soft or fine aeolian sounds.

In the accompanying drawings, Figure 1 is a sectional view of a piano-action with my improved stop-rail and back-check, showing the key depressed, the hammers near the string, and the back-check held by the stop-rail. Fig. 2 is a perspective view of an action-bracket and my stop-rail with back-check and hammer-heel.

Similar numerals refer to corresponding parts in the several views.

The numeral 10 is a key of an upright piano, which has the capstan-screw 11 in its rear end. The extension 12 rests on capstan 11 and raises the front end of wippen 13, with jack 14 thereon and hammer 15 in the usual manner in striking string 16. The rear end of the wippen 13 is lowered by the raising of the front end and causes wire-spoon 17 to press out on damper-lever 18, withdrawing damper 19 from the string 16, as usual. The hammer-rail 20 is raised by the usual trap-work and pedal from its normal position, as shown in dotted outline in Fig. 1, to any desired position in holding the hammers in proximity to the strings.

I make my back-checks 22 with an extension 26 at their upper ends, as compared with the old form which is shown in dotted outline at 27. A stop-rail 21 is secured on action-supporting brackets 23 by suitable screws 24 in such a position in the path of back-checks 22 as to prevent the back-check from springing forward against the hammer-butt

heel 15' and blocking the hammer 15 against the string. The openings in rail 21 for screws 24 are made somewhat larger than the screw 55 in order that rail 21 may be adjusted or regulated as desired. The opposing faces of hammer-butt heel 15' and back-check 22 are felted in the usual manner, and the edge 25 of rail 21 is burnished or black-leaded to insure smooth noiseless action.

It is obvious that when, as shown in Fig. 1, key 10 is depressed by the player, and thereby extension 12 raises wippen 13 and back-check 22, the back-check can only advance in its upward-and-forward motion until it strikes stop-rail 21. Stop-rail 21 therefore becomes a positive or fixed limit for such upward motion and is thus a positive means of regulating such upward and forward position of the back-checks, no matter how much the parts may be out of regulation by dampness or other causes. The position of stop-rail 21 is that which has been experimentally found to be the exact position for the back-checks in order to best receive the rebound of the hammer-butt heel and produce the best tonal effects. Rail 21 is capable of regulation or adjustment, as stated; but when once secured in this predetermined position it is positive and uniform in its reception of the faces of the back-checks and forms the upper limit of their journey. It is also apparent that pressing the back-checks against the straight-edge of my stop-rail keeps the back-checks in true line and in correct position, and that thus the stop-rail controls or regulates the position of the back-checks, as stated.

All who are skilled in the art of piano making and regulating realize the care and skill which must be exercised in adjusting back-checks 22 in order that they shall rightfully perform their office; but after the highest skill has been exercised it is found that dampness will cause the wood parts of the action to swell, forcing checks 22 forward sufficiently to cause the blocking of the hammers solid against the strings instead of having room to spring back against the back-check, as they should. Damp climates and wet seasons have thus caused trouble for the most careful workmen.

It is apparent at once that my simple stop-rail 21 and extension 26 of back-checks 22 en-

tifully overcomes this difficulty and also makes it easier to adjust checks 22. When once the stop-rail 21 is rightly adjusted, it is apparent that it will remain a positive uniform means of regulation for the back-checks. I have also found that when the hammers are held in close proximity to the strings, as shown in Fig. 1, and the keys are touched lightly the most beautiful soft tonal effects may be produced, as of an aeolian harp. Without my stop-rail the back-checks spring forward and block such light touches on the strings; but with it the hammers are free to be actuated by the lightest touches on the keys, thus producing new and most pleasing effects.

What I claim as new, and desire to secure by Letters Patent, is—

1. In a piano-action, suitable wippens and means for actuating the same, back-checks on said wippens and moved thereby, and a positive regulating means to limit said movement of the back-checks.
2. In a piano-action, suitable wippens and means for actuating the same, back-checks on

said wippens and actuated thereby, a stop-rail 25 to limit said movement of the back-checks.

3. In a piano-action having suitable hammers and means for actuating the same, back-checks having felt-faced extensions, and a positive stop-rail to receive said felt-faced extensions.

4. A piano-action having suitable supporting-brackets, wippens having jacks thereon and means for actuating said wippens, hammers actuated by said jacks, back-checks on 35 said wippens and actuated thereby, a regulating-rail for the back-checks on said brackets, and a straight side to said rail to receive said back-checks and equalize their movement.

In testimony whereof I have signed my name to this specification in the presence of two subscribing witnesses.

CHARLES A. AHLSTROM.
